UNITED STATES PATENT OFFICE.

MORTON G. BUNNELL, OF CHAMPAIGN, ILLINOIS.

SPARK-PLUG.

1,273,819.

Specification of Letters Patent. Patented July 30, 1918.

Application filed April 4, 1917. Serial No. 159,650.

To all whom it may concern:

Be it known that I, MORTON G. BUNNELL, a citizen of the United States of America, and resident of Champaign, Champaign county, Illinois, have invented a certain new and useful Improvement in Spark-Plugs, of which the following is a specification.

My invention relates to spark plugs of that kind in which means are provided for readily removing the insulator from the socket without the use of tools.

It will be seen that this is an improvement on the spark plug disclosed in my prior application, No. 77,573.

15 Objects of my invention, as herein shown and described, are to provide an improved construction and arrangement whereby, in a spark plug of this kind, the metal jacket of the insulator cannot rotate in the socket 20 which is screwed into the engine cylinder; to provide an improved construction whereby, in a spark plug of this construction, the inner end of the metal jacket will be provided with a resilient cushion, thus making 25 it practical to use certain devices for forcing the insulator and its jacket tightly into the socket, and at the same time insuring a gas-tight joint where the inner end of the jacket is seated against the shoulder inside of the 30 socket; and to provide an improved construction whereby, in the use of certain devices for forcing the insulator and its jacket tightly into the socket, the said devices will be adapted to firmly lock the different parts 35 against displacement, thus preventing the insulator and its jacket from being forced out of the socket by the pressure in the engine.

To these and other useful ends, my invention consists in matters hereinafter set forth and claimed.

In the accompanying drawings:

Figure 1 is a side elevation of a spark plug embodying the principles of my invention.

Fig. 2 is a side elevation of the socket or bushing which is screwed into the engine cylinder.

50 Fig. 3 is a side elevation of the insulator and its jacket, and the pivoted bail or locking device, showing the same withdrawn from the socket.

Fig. 4 is a vertical section of said spark plug, showing the insulator in side elevation,

but showing the insulator jacket and the 55 socket in section.

Fig. 5 is a plan of the socket shown in Fig. 2.

Fig. 6 is a plan of the parts shown in Fig. 3.

Fig. 7 is a perspective of the split beveled 60 steel ring.

Fig. 8 is an enlarged detail sectional view of one side of the ring shown in Fig. 7, showing the adjacent portions of the structure, and illustrating the manner in which said ring is contracted when the insulator and its jacket are forced into the socket-member by the locking device.

As thus illustrated, my invention 70 comprises a metal bushing or socket piece A

provided at its smaller end with a threaded portion *a* to screw into the cylinder of the engine. Internally, the socket A is provided with an upper shoulder 1 and a lower shoulder 2, formed by reductions in the diameter of the bore of the socket. The insulator B is of any suitable material, and is provided with the usual electrodes *b* for producing the spark at the other end of the plug. A 80 metal jacket C surrounds the upper portion of said insulator, the lower end of said jacket being beveled at *c*, and a washer 3 of soft material and a steel ring D being interposed between the shoulder 1 and the 85 bevel *c*, thus forming a tight joint. The ring D, it will be seen, is beveled at *d* to engage the bevel *c*, and is split at 4, whereby this ring will contract as the jacket C is forced downward, and when the ring 3 of 90 soft material is compressed, thus providing a resilient cushion for the inner end of said jacket. The outer end of the insulator B is provided with a screw terminal 5, and a washer 6 of insulating material is slipped 95 over said screw and held in place by the nuts 7 and 8 by which the electrical connection is made to the plug. The insulator B is provided with a shoulder 9 upon which the ring 3 is supported, and when the nuts 7 and 8 are screwed down against the washer 6, which latter bears against the outer end of the jacket C, the inner end of the latter is forced against the ring D, with the result that the ring 3 is forced against the shoulder 9, so that devices are provided at the inner and outer ends of the jacket to removable hold the jacket in place on the insula- 100 105

tor, whereby the insulator and its jacket can be removed as a unit from the socket. The ring D, of course, is removable from the outer end of the insulator, as the washer 6 is removed.

To hold the insulator and its jacket within the socket, the latter is provided externally with lateral projections E having rollers e, and the jacket C is provided with lateral pivots F for the bail f which forms the handle for the removable insulator and jacket. This bail has cam portions 10 which bear against the upper sides of the rollers e to force the insulator and its jacket out of the socket, when the bail is thrown over to the position shown in Fig. 3, and is also provided with cams 11 which pass below and engage the under sides of the rollers e when the bail is thrown into the position shown in Fig. 1, thereby to force the insulator and its jacket down into the socket. The hub portions of the bail f are also provided with depressions 12 which finally engage the under sides of said rollers e to allow the insulator and its jacket C to move slightly outward in the socket, and to lock the bail in the position shown in Fig. 1, thus preventing unlocking of the plug during the operation of the engine. When the depressions 12 reach the rollers e, the jacket C is given said outward movement by the action of the ring D, which latter by its resilient action, after being slightly compressed by the engagement of the cams 11 with the under sides of the rollers e, expands sufficiently to produce this slight outward movement of the jacket C when the bail f reaches its final position. The cams 11 exert a powerful pressure on the under sides of the rollers e, and with such a locking device it is not desirable to have the inner end of the jacket or sleeve C encounter an unyielding shoulder or seat in the plug-structure, as the cams 11 do not yield, and in order to bring the bail into locking position, with the insulator and its jacket firmly in the socket, there must be a slight yielding action somewhere, and this is taken care of by the resilient ring D which contracts during the action of said cams and then immediately expands to force the jacket C slightly outward and keep the rollers e firmly seated in the depressions 12 on the hub portions of the bail.

Furthermore, it will be seen that the socket A is provided at its outer end with notches G at each side thereof, and that these notches receive the inner portions 13 which are rigid with the jacket C, and to which the pivots F are suitably secured. When the portions 13 are in the notches G, the jacket C cannot rotate in the socket A, and the removable elements of the spark plug structure will always be brought into such position, when inserted in the socket, that the pivots F will be directly above the

rollers e, so that the cams 11 will simultaneously engage these rollers when the bail is swung over into locking position. This prevents turning or twisting of the jacket in its socket, and insures the proper action of the locking device when the insulator and socket are to be forced down in the socket and locked therein.

It will be seen, therefore, that the washer and ring 3 and D and the washer 6 serve as devices for removably holding the sleeve C on the insulator B, the shoulder 9 cooperating, of course, with the washer 3 and the ring D to form one of said devices. In other words, these devices hold said sleeve against endwise displacement on the insulator, but inasmuch as one of the devices (the washer 6) is removable, it follows that these devices as a whole are of such character that the sleeve or jacket can be readily removed from the insulator. With the construction shown and described, the said sleeve or jacket C, which may be of steel, forms a bottomless receptacle for the insulator, said receptacle having the bail f pivoted thereon to form a handle therefor, so that the bail not only forms a lever by which to operate the cam devices for forcing the insulator and jacket into and out of the socket, but serve also as a handle by which to lift said jacket and insulator out of the socket-member A when such is necessary or desirable. The shoulder 2 will serve to limit the downward movement of the insulator in the socket-member, and a slight space can be left above this shoulder, below the shoulder 14 on the insulator, to permit the downward movement of the insulator when the cams 11 engage the lower sides of the rollers e, or this space can be occupied by a soft washer similar to the washer 3, thus further insuring against leakage. These washers can be made of any suitable material, such as thin copper and asbestos, and need not have any springy or resilient action, inasmuch as the resilient effect is provided by the steel ring D, which latter is very strong and springy, and which serves by its expansion to immediately lift the insulator and its jacket, to a slight extent, as soon as the bail f is thrown into the position shown in Fig. 1, so that the rollers e rest in the depressions 12 in the cams on the hubs of the bail. The force by which the ring D is contracted is not communicated through the insulator, but directly from the jacket, so that there is no danger of breaking the insulator.

Of course, when the insulator B has been forced down as far as possible, so that the shoulder 14 bears hard against the shoulder 2, any further action of the cams 11 on the rollers e will then cause the sleeve or jacket C to slide downward upon the insulator, and it is at this time (at the same time that the

washer 3 is compressed on the shoulder 1) that the contraction of the spring ring D takes place to permit the further downward movement of the jacket C, thereby to prevent breakage. Thus the ring D and the washer 3 form a sort of stuffing box or gland for the cylindric upper portion of the insulator B, which latter may be of porcelain or other suitable material, thereby to not only prevent leakage while the engine is in operation, but also to prevent breakage when the insulator and its jacket are inserted and locked in position. When the washer 6 is screwed down upon the upper end of the jacket C, the adjustment is such that the ring D and the washer 3 are compressed to a slight extent against the shoulder 9. During the operation of the cams 11, therefore, any further downward movement of the jacket C will bring the upper end of this jacket a slight distance below the washer 6, causing the ring B to very tightly hug the insulator B (see Fig. 8). But when the rollers e rest in the depressions 12 (see Fig. 1), the ring D will then again expand a little, and this causes the upward movement of the jacket C on the insulator, thereby reducing the space between the under side of the washer 6 and the top of the jacket. Should the pressure in the engine tend to raise the insulator B, during the operation of the engine, by a slight or possible further compression of the washer 3, the ring D will be lifted against the bevel e on the lower end of the jacket, thus causing the ring to again contract very tightly, so that this ring D, which is of less internal diameter than the annular shoulder 9 on the insulator, not only coöperates with the jacket and other elements to prevent the insulator from being forced out of the plug by the pressure, but also serves to prevent leakage of the pressure.

I do not limit myself to the exact construction shown and described.

45 What I claim as my invention is:—

1. A spark plug comprising a metal socket-member adapted to be attached to the cylinder of an internal-combustion-engine, an insulator adapted to enter said socket-member, a metal jacket inclosing the outer portion of said insulator and adapted to enter the socket-member, a bail provided with hub-portions, means to pivot said hub-portions upon the opposite sides of said jacket, said socket-member having notches to receive said means to prevent rotation of said jacket therein, whereby the jacket is locked against rotation, lateral projections on the socket-member, means carried by said hub-portions to engage said projections and thereby hold said insulator and jacket tightly within the socket-member when said bail is moved in one direction, and means on the insulator to engage the opposite ends of the jacket, so that said jacket forms a bottomless receptacle

for said insulator, and whereby said bail forms a swinging handle for said receptacle.

2. A spark plug comprising a metal socket-member adapted to be attached to the cylinder of an internal-combustion-engine, an insulator adapted to enter said socket-member, a metal jacket inclosing the outer portion of said insulator and adapted to enter the socket-member, a bail provided with hub-portions, means to pivot said hub-portions upon the opposite sides of said jacket, said socket-member having means to prevent rotation of said jacket therein, whereby the jacket is locked against rotation, lateral projections on the socket-member, means carried by said hub-portions to engage said projections and thereby hold said insulator and jacket tightly within the socket-member when said bail is moved in one direction, and means to removably secure said jacket on said insulator, said bail having a lever handle for the operation thereof and by which to lift said jacket and insulator out of the socket-member.

3. A spark plug comprising a metal socket-member adapted to be attached to the cylinder of an internal-combustion-engine, an insulator adapted to enter said socket-member, a metal jacket inclosing the outer portion of said insulator and adapted to enter the socket-member, a bail provided with hub-portions, means to pivot said hub-portions upon the opposite sides of said jacket, said jacket having lateral projections to engage said socket-member and prevent rotation of the jacket therein, whereby the jacket is locked against rotation, lateral projections on the socket-member, means carried by said hub-portions to engage said projections and thereby hold said insulator and jacket tightly within the socket-member when said bail is moved in one direction, and means to secure said jacket on said insulator, so that said jacket is rendered removable from the socket-member by a single movement of said bail.

4. A spark plug comprising a metal socket-member adapted to be attached to the cylinder of an internal-combustion-engine, an insulator adapted to enter said socket-member, a metal jacket having a beveled inner end inclosing the outer portion of said insulator and adapted to enter the socket-member, a bail provided with hub-portions, means to pivot said hub-portions upon the opposite sides of said jacket, lateral projections on the socket-member, means carried by said hub-portions to engage said projections and thereby hold said insulator and jacket tightly within the socket-member when said bail is moved in one direction, and devices on the insulator to engage the opposite ends of the jacket, so that said jacket forms a bottomless receptacle for said insulator, and whereby said bail forms a swinging handle for said receptacle, one of

said devices comprising a resilient split beveled ring forming a cushion for the inner end of said jacket, said socket-member having a shoulder to support said ring, whereby
5 the ring is contracted by the operation of said bail.

5. A spark plug comprising a metal socket-member adapted to be attached to the cylinder of an internal-combustion-engine, 10 an insulator adapted to enter said socket-member, a metal jacket inclosing the outer portion of said insulator and adapted to enter the socket-member, a bail provided with hub-portions, means to pivot said hub-portions upon the opposite sides of said jacket, lateral projections on the socket-member, means carried by said hub-portions to engage said projections and thereby hold said insulator and jacket tightly within the
20 socket-member when said bail is moved in one direction, and devices to removably secure said jacket on said insulator, said bail having a lever handle for the operation thereof and by which to lift said jacket and
25 insulator out of the socket-member, one of said devices comprising a resilient cushion for the inner end of said jacket and said socket-member having a shoulder to support said cushion.

30 6. A spark plug comprising a metal socket-member adapted to be attached to the cylinder of an internal-combustion-engine, an insulator adapted to enter said socket-member, a metal jacket having a beveled
35 wire end and inclosing the outer portion of said insulator and adapted to enter the socket-member, a bail provided with hub-portions, means to pivot said hub-portions upon the opposite sides of said jacket, lateral
40 projections on the socket-member, means carried by said hub-portions to engage said projections and thereby hold said insulator and jacket tightly within the socket-member when said bail is moved in one direction,
45 and devices to secure said jacket on said insulator, so that said jacket is rendered removable from the socket-member by a single movement of said bail, one of said devices comprising a soft washer and a split beveled
50 steel ring which forms a gas-tight cushion for the inner end of said jacket, and said socket member having a shoulder to support said cushion, whereby the ring is contracted by the operation of said bail.

55 7. A spark plug comprising a metal socket-member adapted to be attached to the cylinder of an internal-combustion-engine, an insulator adapted to enter said socket-member, a metal jacket inclosing the outer
60 portion of said insulator and adapted to enter the socket-member, a bail provided with hub-portions, means to pivot said hub-portions upon the opposite sides of said jacket, lateral projections on the socket-member,
65 means carried by said hub-portions to en-

gage said projections and thereby hold said insulator and jacket tightly within the socket-member when said bail is moved in one direction, having provisions to permit slight outward movement of said jacket 70 after said bail is fully adjusted, and devices on the insulator to engage the opposite ends of the jacket, thereby to hold the insulator against displacement from the jacket, and so that said jacket forms a bottomless receptacle for said insulator, and whereby said bail forms a swinging handle for said receptacle, one of said devices comprising a resilient cushion to produce said outward movement of the jacket, and said socket-member having a shoulder to support said cushion.

8. A spark plug comprising a metal socket-member adapted to be attached to the cylinder of an internal-combustion-engine, 75 an insulator adapted to enter said socket-member, a metal jacket inclosing the outer portion of said insulator and adapted to enter the socket-member, a bail provided with hub-portions, means to pivot said hub-portions upon the opposite sides of said jacket, lateral projections on the socket-member, means carried by said hub-portions to engage said projections and thereby hold said insulator and jacket tightly within the
80 socket-member when said bail is moved in one direction, having depressions on the hubs to permit slight outward movement of said jacket after the bail is fully adjusted, and devices to removably secure said jacket 100 on said insulator, said bail having a lever handle for the operation thereof and by which to lift said jacket and insulator out of the socket-member, one of said devices comprising a resilient cushion to produce 105 said outward movement of the jacket, and said socket-member having a shoulder to support said cushion.

9. A spark plug comprising a metal socket-member adapted to be attached to the cylinder of an internal-combustion-engine, 110 an insulator adapted to enter said socket-member, a metal jacket inclosing the outer portion of said insulator and adapted to enter the socket-member, a bail provided with hub-portions, means to pivot said hub-portions upon the opposite sides of said jacket, lateral projections on the socket-member, means carried by said hub-portions to engage said projections and thereby hold 115 said insulator and jacket tightly within the socket-member when said bail is moved in one direction, having rollers on said lateral projections, with seats on said hubs to receive said rollers and permit slight outward 120 movement of said jacket after said bail is fully adjusted, and devices to secure said jacket on said insulator, so that said jacket is rendered removable from the socket-member by a single movement of said bail, one 125 130

of said devices comprising a resilient cushion to produce said outward movement of the jacket.

10. A spark plug comprising a metal socket-member adapted to be attached to the cylinder of an internal-combustion-engine, an insulator adapted to enter said socket-member, a metal jacket inclosing the outer portion of said insulator, adapted to enter the socket-member, a metal spring encircling the insulator and engaging the inner end of said jacket, said insulator and socket-member having shoulders to form a seat for said spring, so that said spring and jacket are carried by said insulator and are removable from the outer end thereof, and means for forcing the jacket inward to compress said spring.

11. The said spark plug, as set forth in claim 10, in which said spring consists of a split metal ring, said jacket having a bevel to engage and thereby contract the ring when the jacket is forced inward.

12. The said spark plug, as set forth in claim 10, in which said spring is provided with means to form a stuffing box or gland to prevent leakage of the engine pressure.

13. In a spark plug, the combination of a socket-member adapted for attachment to an

internal combustion engine, an insulator for insertion in said socket-member, means carried by said insulator to produce the spark for causing ignition in said engine, devices to force the insulator inward and hold it in place in said socket-member, and means including a metal spring to yieldingly resist the inward movement of said insulator and to prevent leakage of pressure from the engine, said devices including a sleeve held against rotation during the operation thereof to compress the spring, and said spring providing a resilient metal cushion.

14. A structure as specified in claim 13, in which said spring is in the form of a metal ring which is split to contract upon the insulator when the insulator is forced inward, which ring is beveled, and means to engage the bevel of the ring to produce said contraction thereof.

15. A structure as specified in claim 13, in which said spring is directly subject to the action of said devices, so that the pressure exerted by said devices against said spring is not communicated thereto through said insulator.

Signed by me at Chicago, Illinois, this 26th day of March, 1917.

MORTON G. BUNNELL.
